JAMES W. SMITH, OF CHARLESTOWN, MASSACHUSETTS.

Letters Patent No. 88,988, dated April 13, 1869.

IMPROVED FOLDING-TABLE.

The Schedule referred to in these Letters Patent and making part of the same.

To all whom it may concern:

Be it known that I, JAMES W. SMITH, of Charlestown, in the county of Middlesex, and State of Massachusetts, have invented an Improved Table; and I do hereby declare that the following, taken in connection with the drawings, which accompany and form part of this specification, is a description of my invention sufficient to enable those skilled in the art to practise it.

My invention relates to the construction of tables for dipping-rooms, kitchens, laundries, and other places, with reference to provision for folding such a table, so that it may be stood up at the side of a room, and may be more safely transported or packed away.

My invention consists in combining with a cross-legged frame, (the two adjacent legs of which, at each end of the table, are hung and turn upon a pivot,) a table-top, made in two parts, hinged together and to the legs, the two parts of the table-top folding together over the leg-frame, as the legs are folded, and assuming a horizontal position, as the legs are spread. It is in this construction that my invention consists.

The drawings represent a table embodying my improvement.

A shows a cross-section of the open table.

B, an end view of the table folded up.

C, a side view of the table.

a and b denote the two legs at each end of the table, pivoted together, at the centre, by a pin, c, and connected to the corresponding legs at the opposite end of the table, by the cross-bars d.

The legs of each pair turn freely on the pin c, so that

each two legs pivoted together, open, as seen at A, or close together, as seen at B.

To the top of each two legs, a or b, connected, by the bars d, is hinged a top-piece, or leaf, e, or f, as seen at i, and the two pieces e f are hinged together, as seen at g.

When the legs are spread open, the leaves, or pieces e f are brought into horizontal position, the adjacent edges of the two leaves butting, as seen at A.

When the parts are in this position, they are held relatively stationary, by hooks h, hung from the hinges g, and hooking into eyes k, at the junction of the legs, or by other suitable devices, and the tops of the two parts e f thus constitute a flat and rigid table-surface.

To fold the table, the hooks are released, and the leaves e f are brought down into vertical position, the legs and leaves assuming the position shown at B, in which position of parts the table may be packed for transportation, so as to be preserved from injury, or may be stood up at the side of a room, or in a closet, where space has to be economized in dwelling-houses.

The invention is applicable to tables used for multifarious purposes, and tables embodying this improvement can be very strongly as well as cheaply made.

I claim the combination with the cross-legs a b, jointed together, of the leaves e f, jointed together and to the legs a b, and a fastening-device, substantially as shown and described.

Witnesses:

JAMES W. SMITH.

FRANCIS GOULD,

J. B. CROSBY.
